Term of patent 14 years

Int. Cl. D9—01

U.S. Cl. D9—101

FIG. 1

FIG. 2

FIGURE 1 is an elevational view of a jar, showing my new design; and,

FIGURE 2 is a top plan view thereof.

The side opposite that seen in FIGURE 1 is the same in appearance as the side shown.

The dominant features of my design reside in the portions shown in full lines.

I claim:

The ornamental design for a jar, substantially as shown and described.
